CONTAINER FOR LIQUID PRODUCTS

Herbert W. Galer, Circleville, Ohio, assignor to United States Steel Corporation

Filed July 12, 1971, Ser. No. 161,411

Term of patent 14 years

Int. Cl. D9—03

U.S. Cl. D9—175

FIG. 1.

FIG. 2.

FIG. 1 is a top plan view of a container for liquid products embodying my new design; and

FIG. 2 is an elevational view.

I claim:

The ornamental design for a container for liquid products, as shown.
